UNITED STATES PATENT OFFICE.

WILLIAM H. LEWIS, OF HUNTINGTON, ASSIGNOR TO THE E. & H. T. ANTHONY & COMPANY, OF NEW YORK, N. Y.

PHOTOGRAPHIC CAMERA.

SPECIFICATION forming part of Letters Patent No. 439,804, dated November 4, 1890.

Application filed March 5, 1890. Serial No. 342,729. (No model.)

To all whom it may concern:

Be it known that I, WILLIAM H. LEWIS, a citizen of the United States, and a resident of Huntington, in the county of Suffolk and State of New York, have invented certain new and useful Improvements in Photographic Cameras, of which the following is a specification.

My invention relates to improvements in photographic cameras; and it consists in novel construction and operation of the parts of the apparatus adjacent to and coacting with the ground-glass frame and the plate-holding frame.

In certain respects my present invention is allied to that for which I obtained a patent dated March 27, 1888, and numbered 379,964, upon which invention this present one is in part an improvement.

In the drawings the same reference-letters indicate the same parts in all the figures.

Figure 1 is an elevation of the invention, partly broken away. Fig. 2 is a side view of the rear part of the camera-box and of the ground-glass holder, partly broken away, showing the holder as in position against the rear of the camera-box. Fig. 3 is a view similar to Fig. 2, showing the ground-glass holder as retracted away from the rear of the camera-box. Fig. 4 is a detail showing the method of securing the ground-glass holder against the rear side of the plate-holder when it is in position. Fig. 5 is a view of the bottom edge or side of the apparatus shown in Fig. 1.

A is the rear of the camera-box.

B is a flat frame, which is held to the rear of the camera-box by spring-clips C C, &c., or in any other suitable manner.

D D are two raised ribs, formed on the back of the flat frame B, upon the upper edges of which, respectively, are fastened springs E E and metallic pieces F F.

G G is the ground-glass frame. The ground glass is held in it by metallic clips H H, which have parts I I, &c., which overlap the glass J, or in any other suitable manner.

K K are pieces of metal fastened to the outer side of the glass-frame G, which, extending laterally therefrom, turn at right angles and pass inwardly toward the camera through slots L L, made in the metallic pieces or plates F F. The inner ends of these metallic parts

K K, after passing through slots K' K', made in the flat frame B, are received within and protected by hoods or casings M, of wood or other suitable material, fastened to the inner side of the flat frame B.

The springs E bear, respectively, upon the pieces of metal K K and normally tend to press them and the ground-glass frame toward the flat frame B. The slots in the metal plates F F are of such dimensions relative to the width and thickness of the metallic pieces K K that they have free movement through them. At or near their free ends the pieces K K are provided with notches N, (see Figs. 2 and 4,) and immediately above them there are other notches, one in each piece K, (marked O.) The outermost edge O' of these notches is cut on a bevel, as shown.

O² O² are cross-pieces at the ends of the parts K of such length that they cannot pass through the slots L in the plates F, but can pass through the slots K' in the flat frame.

P P' are strips, preferably of metal, although they may be upwardly-extending wooden or other parts of the frame B, which serve to hold the sensitive-plate holder in position.

X is a pull-strap for manipulating the ground-glass frame.

The operation of the apparatus is as follows: The focus is obtained and the picture is brought properly within the field while the ground-glass frame is close against the rear of the camera, as shown in Fig. 2. When in this position, the ground-glass frame is in exactly the position which the sensitive surface subsequently occupies. When this is done, the pull-strap X is grasped and pulled outwardly and somewhat upwardly or laterally, as the case may be, which causes the ground-glass frame to tilt on the axis formed by the contact between the springs E and the metal pieces F, and the springs are put under tension as the ground-glass frame moves outwardly or away from the camera when it has assumed a position in which the cross-pieces O² come in contact with the plates F. Then a slight pull upwardly or laterally on the strap, supplemented by the endwise thrust of the springs E, sets the edges F' of the plates F into the notches N of the metallic pieces K. Thus the ground-glass frame is held retracted.

against the stress of the springs E. The plate-holder containing the sensitive plate or surface, whatever it may be, is then slid into its place between the retracted ground-glass frame and the end of the camera-box until it fits properly against the rear thereof between the raised strips or ledges P P. The ground-glass frame is then pressed backwardly or downwardly again, as the case may be, until the notches N release their hold, and then the springs E instantly press the ground-glass frame snugly against the rear of the plate-holder, confining it in place; but in order that it may not be moved, however slightly, at the time of drawing the slide the ground-glass frame is then again pulled in a direct line across the rear of the camera, which causes the same edge F' of the plate F to enter the second notch O in the piece K. The beveled side O' whereof then exerts a cam-like action, and the ground-glass frame is crowded firmly against the rear of the plate-holder, which is thus rigidly locked in position and cannot be moved by such force as will be exerted upon it by the act of drawing the slide.

The advantages of my present invention as compared with my former one are many. Among them, the means of sustaining, guiding, and holding the ground-glass plate—*i. e.*, the parts K K, are attached to the ground-glass frame and extend inwardly and are protected by the other adjacent parts, whereas in the former construction the equivalents of these parts projected rearwardly when the ground-glass frame was closed against the camera, and were therefore liable to catch in passing articles of clothing, &c., and also to become bent and useless; also, in my former construction I had no means for positively locking the plate-holder against movement consequent on drawing the slide.

I claim—

1. The combination, in a photographic cam-

era, of a spring-controlled ground-glass holder 45 and two supports therefor, which coacting with the springs sustain the holder in two positions, one of them coincident with the surface on which the picture is to be taken and the other sufficiently rearward thereof to allow of 50 the insertion of the plate-holder, the supports having inclined notches whereby the ground-glass frame may be crowded against the frame supporting the sensitive surface, substantially as set forth.

2. The combination, in a photographic camera, of a ground-glass holder having upon its sides notched supports projecting toward the camera and springs which engage with the supports and coacting with them hold the 60 plate in two positions, the supports being provided with a notch adapted to engage with a suitable device on the main frame, whereby the ground-glass frame may be crowded against the frame supporting the sensitive 65 surface, substantially as set forth.

3. The combination, in a photographic camera, of a ground-glass holder having upon its sides supports which extend toward the camera, which supports engage with springs attached to the main frame and normally press the ground-glass frame toward the camera, said supports being provided with a plurality of notches, one of which in each support engages with a suitable device on the main 75 frame, whereby the ground-glass frame is supported in its most rearward position, and the others engaging with said devices press the ground-glass frame against the support for the sensitive surface, substantially as set 80 forth.

Signed at New York, in the county of New York and State of New York, this 27th day of February, A. D. 1890.

WILLIAM H. LEWIS.
